United States Patent Office

Des. 185,474
Patented June 9, 1959

185,474

MIRROR BRACKET OR SIMILAR ARTICLE

Arthur Waller, Highland Park, Ill.

Application September 20, 1957, Serial No. 47,785

Term of patent 14 years

(Cl. D17—12)

FIG. 1

FIG. 2

FIG. 3

Fig. 1 is a front perspective view of a mirror bracket showing my design.

Fig. 2 is an elevational side view; and

Fig. 3 is a plan view.

The dominant feature of my design resides in the front flange portion which is bevelled as shown.

I claim:

The ornamental design for a mirror bracket or similar article, as shown and described.
